UNITED STATES PATENT OFFICE.

WESLEY W. MOORE, OF OLNEY, TEXAS.

SELF-LUBRICATING ROD-LINE CARRIER.

Application filed June 6, 1927. Serial No. 196,940.

This invention relates to supporting guides or carriers and aims, among other objects, to provide an improved self-lubricating guide for power rods such as are employed in oil fields.

In the accompanying drawings:

Fig. 1 is a side elevation of a series of supporting guides embodying my improvements and showing a rod line supported thereby;

Fig. 2 is a top plan view of the guides shown in Fig. 1;

Fig. 3 is a perspective view of one of the guides; and

Fig. 4 is a central sectional view, parts being shown in elevation.

In the operation of a series of oil wells it is customary to provide a central power station which supplies the power to operate the individual pumps by means of a series of reciprocating rods connected to pump jacks or the like. Rod lines several thousand feet long are not uncommon. Such rod lines are usually supported above the ground on guides which require more or less frequent lubrication and this involves some expense for maintenance.

To the end of providing improved rod line guides which are self-lubricating and to dispense with the necessity for heavy maintenance cost, I have shown the preferred embodiment of the invention as comprising guide blocks 10, each having a self-contained lubricant reservoir 11 arranged to supply oil by gravity through a duct 12 to the lower end of a wick 13 which becomes saturated and supplies sufficient oil to a rod 14 reciprocating in a guiding groove 15.

Herein, the block is substantially L-shaped and the reservoir is formed in the vertical branch; while the guiding groove 15 is formed on the ledge of the horizontal branch. The block is preferably cast or made in one piece, the reservoir being formed by a suitable core and the duct being drilled or bored.

The blocks may be supported by any suitable means, but I prefer to mount them on pieces of pipe 16 driven into the ground and to provide integral pins or stems 17 on the blocks to be telescoped into the upper ends of the pipes. Hence, they may easily be assembled or dismantled.

To prevent rain or dust from accumulat-

ing on the oil, I have shown a hinged or pivoted cover plate 18 adapted to be pushed aside or opened when it is necessary to refill the reservoir.

From the foregoing description it will be seen that my improved guides may be manufactured very cheaply and that they are very easily installed. Moreover, each one will carry a supply of oil that will last several months, thus eliminating the necessity for employing an oiler. Further, since all of the guides are self-lubricating, they do not wear out or wear the rods due to the negligence of an attendant. If the old guides now in use are neglected by the oiler, the wear on the rods operating under heavy load will quickly cause them to break and the loss of time repairing a rod entails stopping a pump.

Obviously the present invention is not restricted to the particular embodiment thereof herein shown and described. Moreover, it is not indispensable that all the features of the invention be used conjointly, since they may be employed advantageously in various combinations and subcombinations.

What I claim is:

1. A rod line guide and carrier comprising, in combination; a substantially L-shaped block presenting a ledge having a rod receiving and guiding groove; a lubricant reservoir in the vertical leg, said reservoir extending above the ledge; a duct to supply lubricant to the groove; a stem formed on the lower side of the block; and a tubular support to receive the stem.

2. A rod line carrier comprising, in combination, a substantially L-shaped block presenting a ledge having a rod receiving and guiding groove; a lubricant reservoir formed in the vertical leg and extending above the ledge, a U-shaped duct formed in the block and connecting the bottom of the reservoir with the bottom of the groove; a wick in said duct; a depending stem formed on the lower side of the block; and a tubular support to receive said stem.

In testimony, that I claim the foregoing as my own, I have hereto affixed my signature.

WESLEY W. MOORE.
